UNITED STATES PATENT OFFICE.

RALPH E. MILLER, OF PARSHALL, NORTH DAKOTA.

SWIVEL CONNECTION.

1,270,538.

Specification of Letters Patent. Patented June 25, 1918.

Application filed November 8, 1917. Serial No. 200,973.

To all whom it may concern:

Be it known that I, RALPH E. MILLER, a citizen of the United States, residing at Parshall, in the county of Mountrail, State 5 of North Dakota, have invented a new and useful Swivel Connection; and I do hereby declare the following to be a full, clear, and exact description of the invention, such as will enable others skilled in the art to which 10 it appertains to make and use the same.

This invention relates in general to well drilling appliances, and more particularly to a swivel connection for joining a water discharge pipe to the upper end of a reciprocating string of tubular drill rods, thereby enabling the drill rods to rotate independently of the water discharge pipe and avoiding any twisting of the rubber hose connection between the discharge pipe and 20 the pump.

Further objects of the invention are to provide a device of this character which is comparatively simple and inexpensive in its construction, which can be used in connection with the conventional well drilling appliances, which provides an effective and water-tight joint, and which can be adjusted to take up wear.

With these and other objects in view, the 30 invention consists in certain novel combinations and arrangements of the parts as will more fully appear as the description proceeds, the novel features thereof being pointed out in the appended claims.

35 For a full understanding of the invention, reference is to be had to the following description and accompanying drawings, in which:

Figure 1 is a side elevation of a reciprocating string of tubular drill rods having a swivel connection constructed in accordance with the invention applied to the upper end thereof, portions being broken away.

Fig. 2 is an enlarged longitudinal sectional view through the swivel connection.

Fig. 3 is a transverse sectional view on the line 3—3 of Fig. 2.

Corresponding and like parts are referred to in the following description and indicated in all the views of the drawings by the same reference characters.

Referring to the drawings, the reference character A designates a string of tubular drill rods which is provided at its lower end 50 with a conventional drilling bit B adapted

to be lowered through the casing C of a well, the upper end of the string of drill rods being joined by the swivel connection to the water discharge pipe 1. This pipe 1 is laterally connected to a flexible hose member 2 60 leading to a conventional pump, and is connected at its upper end by suitable suspension means D to a cable 3^a which passes upwardly around the pulley on the derrick and is operatively connected to the usual 65 mechanism for alternately taking it in and letting it out to raise and lower the string A of drill rods during the drilling operation. The upper end of the water discharge pipe 1 is shown as provided with a T-connection 3, the lateral arm thereof being provided with a short curved pipe 4 to which the rubber hose 2 is connected, while the upper end thereof has a plug 5 fitted therein, said plug being formed with a stem 6 70 upon which the yoke 7 is swiveled, said yoke being held in position by the nuts 8. This stem 6 and yoke 7 constitute suspension means D for connecting the upper end 75 of the water discharge pipe to the operating 80 cable 3 of the drilling mechanism.

A barrel 9 surrounds the water discharge pipe 1, the space between the barrel and the pipe being filled with packing 10. A packing nut 11 is threaded upon the upper end 85 of the barrel 9 and arranged to be screwed down whenever it becomes necessary to tighten the packing, said packing nut being formed with a bushing 11^a through 90 which the water discharge pipe extends.

The lower end of the barrel 9 has a sleeve 12 exteriorly threaded thereon, said sleeve being provided at an intermediate point in its length with an inwardly projecting annular flange 13 which surrounds the water 95 discharge pipe 1 and forms an abutment against which the lower end of the packing 10 bears. The lower extremity of the water pipe 1 has a bearing collar 14 threaded thereon, said collar engaging the flange 13 100 of the sleeve 12 and being held in an adjusted position by a lock nut 15. A head 16 is threaded in the lower end of the sleeve 12, said head carrying a tubular section 17 which is arranged in alignment with the 105 water pipe 1 and adapted to be secured by a suitable union 18 to the upper end of the string A of tubular drill rods. The inner face of the head 16 may be formed with a conical seat 16^a, while the lower end of the 110

water pipe 1 and lock nut 15 may be tapered at 15^a for engagement with the seat 16^a, thereby providing a bearing which will resist the up and down thrusts of the tool 5 without interfering in any manner with the rotation of the drill rods and barrel 9 about the water pipe 1 as a center. The head 16 can be screwed into the lower end of the sleeve 12 and brought into proper engagement with the lower end of the water pipe 1, after which it can be locked against working loose by a suitable jam nut 19. This construction also admits of adjustment being readily made to compensate for wear.

10 In the operation of the device the string of drilling rods and swivel connection are raised and lowered by the conventional drilling mechanism, water being forced into the well or pumped from the well through the 20 tubular drill rods, water pipe 1, and rubber pump connection 2. The drill rods are, however, free to rotate independently of the water pipe, thereby avoiding the possibility of twisting the rubber hose connection leading 25 to the pump.

Having thus described the invention, what I claim as new and desire to secure by Letters Patent, is:—

1. In a swivel connection of the character 30 described, the combination of a water pipe provided with a lateral pump connection and having suspension means at the upper end thereof, a packing barrel surrounding the water pipe, packing interposed between the barrel and pipe, a sleeve fitted upon the lower end of the barrel and provided at an intermediate point in its length with an interior flange surrounding the water pipe and providing an abutment for the packing 35 of the barrel, a bearing collar fitted upon the lower end of the water pipe and engaging the flange of the sleeve, and a head fitted in the lower end of the sleeve and provided with a pipe section arranged in alinement with the 40 water pipe, said head engaging the lower end of the water pipe and maintaining the pipe section in communication with the water pipe.

2. In a swivel connection of the character 50 described, the combination of a water pipe having a lateral pump connection and provided at its upper end with suspension means, a packing barrel surrounding the water pipe, packing interposed between the 55 barrel and water pipe, a sleeve fitted upon the lower end of the barrel and provided with an interior annular flange surrounding the water pipe and providing an abutment for the lower end of the packing, a bearing 60 collar threaded upon the lower end of the water pipe and engaging the flange of the sleeve, a lock nut for holding the bearing collar in an adjusted position, a head threaded in the lower end of the sleeve and provided 65 with a pipe section arranged in aline-

ment with the water pipe, said head being adapted to be brought into loose engagement with the water pipe to maintain the water pipe and pipe section in communication, and a lock nut for holding the head in an 70 adjusted position.

3. In a swivel connection of the character described, the combination of a water pipe having a lateral pump connection and provided at its upper end with suspension 75 means, a packing barrel surrounding the pipe, packing fitted within the barrel and the pipe, a sleeve applied to the lower end of the barrel and provided at an intermediate point in its length with an interior annular flange 80 which surrounds the water pipe and provides an abutment for the lower end of the packing, a bearing collar applied to the lower end of the water pipe for engagement with the flange, a head fitted within the lower end of the sleeve and provided with a pipe section arranged in alinement with the water pipe, said head serving to hold the water pipe and pipe section in communication, and one of the members being provided 85 with a seat loosely receiving the other member.

4. In a swivel connection of the character described, the combination of a water pipe having a lateral pump connection and provided at its upper end with suspension 90 means, a packing barrel surrounding the water pipe, packing fitted between the barrel and pipe, a sleeve applied to the lower end of the barrel and provided at an intermediate point with an interior annular flange surrounding the water pipe and providing an abutment for the lower end of the packing, a bearing collar applied to the lower end of the water pipe for engagement with the flange of the sleeve, a lock nut for the bearing collar, said lock nut and water pipe having a tapered end, and a head fitted in the lower end of the sleeve and provided with a pipe section arranged in alinement with the 100 water pipe, said head being provided with a conical seat adapted to receive the tapered end of the water pipe and lock nut thereon.

5. In a swivel connection of the character described, the combination of a water pipe 115 having a lateral pump connection and provided at its upper end with suspension means, a packing barrel surrounding the water pipe, packing fitted between the barrel and pipe, a sleeve applied to the lower end of the barrel and provided at an intermediate point with an interior annular flange surrounding the water pipe and providing an abutment for the lower end of the packing, a bearing collar fitted upon the lower end of the water pipe and engaging the flange of the sleeve, a lock nut for the bearing collar, the lower end of the water pipe and lock nut being tapered, a head threaded adjustably 120 within the lower end of the sleeve and pro-

vided with a pipe section arranged in alignment with the water pipe, said head being provided with a conical seat adapted to loosely receive the conical end of the water pipe and lock nut thereon, and a lock nut for holding the head in an adjusted position.

5 In testimony whereof I have signed my

name to this specification in the presence of two subscribing witnesses.
